UNITED STATES PATENT OFFICE.

LESTER S. RILEY, OF BOSTON, MASSACHUSETTS, ASSIGNOR TO PROGRESS MANUFACTURING COMPANY, A CORPORATION OF MASSACHUSETTS.

UNIVERSAL COUNTER.

1,061,126.

Specification of Letters Patent.

Patented May 6, 1913.

Application filed May 24, 1912. Serial No. 699,518.

To all whom it may concern:

Be it known that I, LESTER S. RILEY, a citizen of the United States, residing at Boston, Roxbury district, Massachusetts, have 5 invented certain new and useful Improvements in Universal Counters, of which the following is a specification.

My present invention relates to improvements in counters or male dies for use in 10 conjunction with the intaglio steel or like dies adapted for embossing note paper and the like.

One object of the invention is to provide a counter which will act as a male die for a 15 larger number of intaglio dies.

A further object is to provide a counter which will give, in conjunction with such intaglio dies, a clear and sharp impression without requiring excessively heavy pressure, 20 thus enabling the embossing to be done by a light portable machine.

My invention is illustrated by the aid of the accompanying drawings in which—

Figure 1 is a sectional elevation. Fig. 2 25 is a similar view at right angles to Fig. 1. Fig. 3 is a plan view of the counter. Fig. 4 is a bottom plan view of the same.

Referring by reference characters to this drawing the numeral 1 designates a metal 30 carrying plate which is provided with a plurality of (preferably two) pins adapted to fit into recesses 2^a of the base of the press, which is indicated conventionally at 2, for the purpose of removably holding it in position.

3 indicates a top or holder which is constructed preferably of sheet metal having overturned edges or flanges on three sides which enables it to be slid onto and into 40 engagement with the carrier, the overturned edges overlapping the edges of the carrier plate as shown. This holder is provided with a central opening 4 of a size somewhat in excess of the intaglio portions of the dies 45 used in conjunction therewith and beneath the plate and extending across the opening is arranged first a layer of kid or thin leather 5 and then and next below a layer of cloth 6.

The opening for convenience is shown as round but of course may be of any suitable or 50 desired shape.

Beneath the cloth and in line with the opening is located a disk of rubber 7 of a size and shape corresponding to the opening and beneath this is a disk of paper or other 55 fiber of similar size and shape indicated at 8. As these disks are of approximately the diameter of the opening they cause the kid to be projected through the opening as shown, forming a raised cushion for the die 9 to act 60 against.

In order to prevent the paper being embossed from catching on the projecting cushion, I provide a spring tongue or deflector 10, preferably integral, as shown.

Having thus described my invention what I claim is:—

1. In combination a carrier plate, a holding plate having a detachable edge connection with the carrier plate and having a central opening, a layer of flexible material between said holding plate and carrier and extending across the opening, and a member of elastic material beneath the layer of flexible material, said member corresponding in size 70 and shape to said opening and being located in line with said opening.

2. In combination with a base, a carrier plate detachably connected thereto, a holding plate having its edges detachably connected 80 to the carrier plate and having a central opening, a layer of flexible material between said plates and extending across the opening, a cushion member beneath said layer and in line with the opening.

3. In combination a carrying plate, a holding plate detachably connected thereto and having a central opening, a layer of kid between said plates and extending across the opening, a layer of fabric extending beneath 90 the layer of kid, a rubber member or square beneath the fabric and in line with the opening and a fiber member forming a support to said rubber member or square, substantially as described.

4. In combination a holding plate having

2
a central opening, a layer of kid extending beneath the holding plate and across the opening, a cushion member beneath said layer and in line with the opening for causing the kid to project through the opening and a deflecting tongue carried by said holding plate, substantially as described.

In testimony whereof, I affix my signature in presence of two witnesses.

LESTER S. RILEY.

Witnesses:

JOHN B. DUPONT,
THOMAS F. KIMBALL.
